UNITED STATES PATENT OFFICE.

JAMES J. HOLMES, OF KANSAS CITY, MISSOURI.

SILO.

1,247,958.

Specification of Letters Patent. Patented Nov. 27, 1917.

Application filed March 14, 1914. Serial No. 824,793.

To all whom it may concern:

Be it known that I, JAMES J. HOLMES, a citizen of the United States, residing at Kansas City, in the county of Jackson and 5 State of Missouri, have invented certain new and useful Improvements in Silos, of which the following is a specification.

This invention relates to silos and has for its object to produce a structure of the 10 character named which can be erected at a minimum cost and possesses the desirable qualities of strength and durability.

A further object is to produce a silo in which the walls are secured in place without 15 the use of nails or other securing devices and are adapted for expansion and contraction in a vertical direction without opening any joints or seams through which rain can enter the silo or through which seepage from 20 the latter can take place.

With these general objects in view, the invention consists in certain novel and peculiar features of construction and organization as hereinafter described and pointed out in 25 the appended claim, and in order that it may be fully understood reference is to be had to the accompanying drawing, in which—

Figure 1, is a fragmentary plan view of a 30 silo embodying my invention;

Fig. 2, is an enlarged section on the line II—II of Fig. 1;

Fig. 3, is a fragmentary plan on a scale much greater than that of Figs. 1 and 2;

Fig. 4, is an elevation of the interior of 35 the silo showing the arrangement of the doors thereof.

Fig. 5, is a vertical section on the line V—V of Fig. 4.

40 In the said drawings, 1 indicates a concrete or equivalent solid and substantial bed to provide settings for a series of posts, each preferably consisting of a central member 2, and two side members 3, secured to the central member by bolts 4 and nuts 5, the inner edges of the flanking members 3 being beveled to provide in conjunction with the adjacent sides of member 2, a pair of V-shaped grooves 6, the bevel of the inner edges of

45 members 3, being determined by the number of posts employed in the erection of the silo, which is adapted to be of polygonal form, though it may vary as regards the number of its sides.

50 To impart stability and strength to the posts, particularly if composed of members

as indicated as preferable, U-shaped clips 7 are fitted around the outer edges of said members and outer sides of the members 3, and the securing bolts 4 extend through 60 said clips. The clips are provided with outwardly projecting lugs 8, as supports for horizontal clamping bands 9 which encircle the silo and guard against outward springing of the posts, and to coöperate with these 65 bands a number of opposite posts may be connected at their upper extremities by tie-rods, each consisting of two members 10 connected by a turn-buckle 11, the ends of the rods extending through the central members of the posts and through the topmost 70 clips 7 and being engaged by clamping nuts 12 which bear against the outer faces of said clips.

The walls of the silo are double and constructed as follows: The outer layer of boards 13 have their upper edges beveled downwardly and outwardly at 14 and their lower edges formed with an obtuse angle shaped groove 15, so that the groove of one 80 board shall snugly receive the beveled upper edge of the immediately underlying board, and the ends of all the boards are beveled so as to converge inward and form an angle corresponding to the angle formed by the 85 sides of the grooved faces of the posts, the boards being of such length as to fit snugly in said grooves and yet be capable of movement in a vertical plane.

The inner part of the silo is composed of 90 boards 16 of exactly the same construction as those described except that they are slightly shorter to fit between the innermost portions of the central members of the posts and are arranged in reverse position, that 95 is to say are arranged so that their beveled upper edges shall slope downwardly and inwardly. Furthermore the boards forming the inner wall are arranged in break-joint relation to the boards forming the outer wall as shown clearly in Fig. 2, and to make the walls air-tight to protect the ensilage against freezing, an insulation 17 of building paper or equivalent material is arranged 100 between the inner and outer walls as shown. 105

At one side the silo will be provided with a wall composed of door and wall sections alternately arranged, see Figs. 4 and 5. In said figures horizontal boards 18, 19, and 110 vertical boards 20 and 21 constitute door frames adapted to be slipped down in the grooves 6 in the same manner that the wall

sections are secured and hinged in each frame is a door 22 adapted to open inwardly and secured to each door are turn-buttons 23 to be turned to lap the outside 5 of the respective door frames and thus secure the door against accidental opening.

The manner of charging this silo with ensilage and removing the ensilage therefrom is the same as that of any other silo, 10 it being noted as hereinbefore suggested, that in wet weather the height of the walls of the silo may increase through expansion and sliding thereof in the grooves of the posts, and that in dry weather contraction of 15 the boards will result in a reduction in the height of the walls, it being further noted that the tension of the tie rods can be varied by proper manipulation of the turn buckles 11, and that the tension of the band 9 can 20 also be varied in the usual and well known manner. It will also be noted that the obtuse angle formation of the upper and lower edges of the boards not only make provision 25 for shedding of moisture away from the walls, but makes each board without the use of nails or the like, support the boards above it without any tendency to act as a wedge to force the supported board outwardly midway between the posts and 30 thereby facilitate outward bowing thereof and the production of open joints.

From the foregoing it will be apparent

that I have produced a silo embodying the features of advantage enumerated as desirable and which is susceptible of modification in minor particulars without departing from the principle of construction involved.

I claim:

A silo comprising a series of upright posts, each provided at its inner corners 40 with a pair of acute angle shaped grooves, walls connecting adjacent posts and composed of substantially horizontal boards fitted together edgewise in superposed relation, the ends of the boards conforming to 45 the angular shape of said grooves and fitting snugly therein, U-shaped clips secured to the posts at different points along the length thereof and provided with outwardly projecting lugs, horizontal clamping 50 bolts encircling the silo and bearing against said clips and upon said lugs, diametric tie rods extending through opposite posts at the upper ends of the same, and through the uppermost clips, and retaining devices 55 secured on the outer ends of said tie-rods and bearing against said clips.

In testimony whereof, I affix my signature, in the presence of two witnesses.

JAMES J. HOLMES.
